UNITED STATES PATENT OFFICE.

LYTTON J. SHIELDS, OF ST. PAUL, MINNESOTA.

DESIGN FOR A STORAGE-BATTERY TERMINAL CONNECTOR.

52,682.

Specification for Design.

Patented Nov. 12, 1918.

Application filed August 8, 1918. Serial No. 249,019. Term of patent 3½ years.

To all whom it may concern:

Be it known that I, LYTTON J. SHIELDS, a citizen of the United States, residing at St. Paul, county of Ramsey, and State of Minnesota, have invented a new, original, and ornamental Design for Storage-Battery Terminal Connectors, of which the following is a specification, reference being had to the accompanying drawings, forming part thereof.

Figure 1 is a perspective top view of the battery connector, showing my new design.

Fig. 2 is a perspective bottom view of the same.

Fig. 3 is a side elevation of the same.

Fig. 4 is a cross section on the line 4—4 of Fig. 3.

The drawing illustrates my ornamental

design of storage battery connector A having hexagonal heads 2 which are connected by the bar or shank 3. The shank 3 of the connector A is formed with a concave recess 4 extending longitudinally along its bottom face.

The hexagonal heads 2 are formed frustum pyramidal shape so that they are smaller at the top than at the bottom having a tapering hole formed centrally through the same for engaging the terminal of a storage battery. The shank 3 is wider at the bottom than at the top.

I claim:

The ornamental design for a storage battery terminal connector as shown and described.

LYTTON J. SHIELDS.
